CLAIM

The ornamental design for a bathroom faucet, as shown and described.

DESCRIPTION

FIG. 1 is an upper perspective view of a bathroom faucet according to the new design.

FIG. 2 is a lower perspective view of the bathroom faucet shown in FIG. 1.

FIG. 3 is a front view of the bathroom faucet shown in FIG. 1.

FIG. 4 is a rear view of the bathroom faucet shown in FIG. 1.

FIG. 5 is a right side view of the bathroom faucet shown in FIG. 1.

FIG. 6 is a left side view of the bathroom faucet shown in FIG. 1.

FIG. 7 is a top view of the bathroom faucet shown in FIG. 1; and,

FIG. 8 is a bottom view of the bathroom faucet shown in FIG. 1.

The broken lines in the drawings depict portions of the bathroom faucet that form no part of the claimed design.

1 Claim, 8 Drawing Sheets
